bon Corporation, a corporation of New York

Application August 31, 1932, Serial No. 631,288

6 Claims. (Cl. 158—27.4)

My invention relates to blowpipes adapted to utilize oxygen and a combustible gas for producing a heating flame. The invention relates particularly to the construction of the gas conduits for preventing flashbacks in the blowpipe.

When a blowpipe is functioning properly the flame produced by the stream of combustible gas issuing from the end of a blowpipe nozzle is separated from the discharge orifice in the nozzle by an unburned portion of the gas stream. If the propagation of the flame towards the orifice is greater than the velocity of the gas stream, the flame travels backward along the unburned portion of the gas stream and recedes into the combustible gas mixture passage. The momentary recession of the flame into the combustible mixture passage is known as a backfire and this phenomenon is usually accompanied by a sharp explosion. If the flame continues to burn within the combustible gas mixture passages this phenomenon is known as a flashback which produces a sizzling noise within the blowpipe. Under a given set of conditions the direct ratio of the number of backfires to the number of flashbacks is known as the flashback resistance of a blowpipe.

When a flashback occurs it is necessary to cut off at least one of the flame supporting gases to extinguish the flashback flame. During the period of the flashback and up until the time the flame is relighted and adjusted the blowpipe is rendered inoperative. If the blowpipe is being used for welding, the strength of the weld is deterioriously affected due to the cooling of the weld during the inoperative period and also due to the subsequent reheating of the weld. If the blowpipe is being used for cutting, the cut may be lost or made ragged as a result of the flame being extinguished. In any event, time and gas are wasted during the inoperative period of the blowpipe.

Heretofore it has been proposed to extinguish the backfiring flame by means of baffles or other constrictions placed in the gas passages. Such devices offer a resistance to the normal forward flow of the gases and are therefore objectionable.

An object of my invention is to increase the flashback resistance of a blowpipe without increasing the resistance to the flow of the gases through the blowpipe passages.

The preferred means of accomplishing the foregoing object is by constructing that portion of either the oxygen passage or the combustible gas passages or both of said passages extending

rearwardly from the discharge end of the mixer nozzle to a minimum distance from the end of said nozzle so that said portion of said passages is free from constrictions adapted to substantially retard the backward flow of the gas therein from the mixing tube throat and by proportioning the length and volume of said portion of said gas passages in accordance with the pressure in the mixing tube throat produced by backfires and also in accordance with the consumption of the acetylene by the blowpipe.

The above and other objects will be more clearly understood from the following description and accompanying drawings, in which

Fig. I is a top view of a blowpipe disclosing one embodiment of my invention.

Fig. II is a longitudinal cross-section of the blowpipe along the line II—II in Fig. I;

Figs. III, IV, V, and VI are enlarged cross-sections of the blowpipe taken on the lines III—III to VI—VI respectively in Fig. I;

Fig. VII is an enlarged sectional view taken on the line VII—VII in Fig. II.

Figs. VIII and IX are respectively top and rear end views of a modification of the blowpipe shown in Figs. I to VII.

Fig. X is a longitudinal view of the blowpipe showing some of the elements in section along the line X—X in Fig. VIII.

Figs. XI to XIII are cross-sectional views along the lines XI to XIII respectively in Fig. X.

Figs. XIV and XV are respectively sectional views of the valve body on the lines XIV—XIV and XV—XV as shown in Fig. IX.

Fig. XVI is a diagrammatic illustration of my invention in its general aspects.

My invention is illustrated herein in reference to metal cutting blowpipes, that is, blowpipes utilizing a preheating flame and a highly oxidizing stream of gas for removing metal. The blowpipe disclosed in the modification shown in Figs. I to VII comprises a handle 1 having a rear valve body 2 and a forward valve body 3 provided with valves for controlling the cutting and heating gases discharged from the blowpipe 4. The blowpipe is supplied with oxygen through a hose (not shown) which is attached to a nipple 5. The nipple 5 is connected to the rear valve body 2 and the passage in the nipple communicates with a passage 6 in the rear valve body 2. A valve 7 in the passage 6 controls the flow of oxygen therein. A tube 8 connects the passage 6 in the rear valve body 2 with an inlet passage 9 in the forward valve body 3.

The oxygen inlet passage 9 in the forward valve

body 3 is divided into a cutting oxygen branch 10, as shown in Fig. IV and a heating oxygen branch 11, as shown in Fig. VI. The cutting oxygen branch 10 is provided with a cutting oxygen valve 12, which is operated by a lever 13 pivoted on a pin 14 on the forward valve body 3. A projection 15 on the valve lever 13 operates the stem 16 of the cutting valve 12 which controls the flow of the oxygen from the valve chamber inlet 17 to the outlet 18 which is connected to a tube 19 leading from the forward valve body 3 to a cavity 20 in the blowpipe head 4.

A nozzle 21 is connected to the blowpipe head 4 by a clamping nut 22. The nozzle 21 has a central cutting oxygen passage 23 therethrough which is connected to the cavity 20 in the blowpipe head 4.

My invention pertains particularly to the conduits for conducting the heating oxygen and combustible gases and the mixture of these gases to the discharge end of the burner nozzle 21 and how they are constructed to prevent flashbacks. The construction of these passages depends upon a number of conditions which will be hereinafter explained. The blowpipe shown in Figs. I to VII is illustrative of a medium pressure blowpipe, that is, a blowpipe using up to 15 lbs. pressure in the acetylene hose. As shown therein the branch heating oxygen passage 11 in the forward valve body 3 is provided with a heating oxygen control valve 24 for controlling the flow of the heating oxygen from the valve inlet chamber 25 to the valve outlet chamber 26 which communicates with a rearwardly extending conduit 27 which is connected to one end of a coiled tube 28 enclosed in the blowpipe handle 1. The other end of the coiled tube 28 is connected to one end of a return conduit 29 and the other end of the return conduit 29 is connected to a passage 30 in the forward valve body 3. The passage 30 leads to the rear portion of the gas mixer 31. In this case the heating oxygen control valve 24 is the first point nearest the mixer nozzle which offers any effective resistance to the gas flowing backward from the discharge end 32 of the mixer nozzle 33 as a result of a backfire. In such a case where all other conditions which may affect the flashback resistance have been determined except the length of and the volume in the passage travelled by the heating oxygen from the heating oxygen valve 24 to the discharge end 32 of the mixer nozzle 33, the length and volume of this passage determines the flashback resistance of the blowpipe. The coiled tube 28 is inserted in the passage as a convenient means for obtaining the desired length of and volume in the passage between the end 32 of the mixer nozzle and the nearest point of resistance to the backward flow to permit the desired recession of backfiring gases into said passage for the prevention of flashbacks as will be hereinafter explained.

The mixer 31 comprises a bore 34 formed in the bottom portion of the forward valve body 3. A portion of the mixer bore 34 is screw-threaded to receive a threaded locking ring 33a which bears against the rear end of the mixer nozzle 33 which is thereby secured in the mixer bore 34. The end of the mixer bore 34 is closed by a screw-threaded plug 35.

A combustible gas such as acetylene is supplied to the gas mixer 31 through a gas hose (not shown) which may be attached to a nipple 36 which is attached to the rear valve body 2. The passage in the nipple 36 communicates with a passage 37 in the rear valve body 2. The flow

of combustible gas in the passage 37 is controlled by a cut-off valve 38. The combustible gas passage 37 in the rear valve body 2 communicates with a tube 39 which connects the passage 37 to a combustible gas passage 40 in the forward valve body 3. The latter passage 40 leads to the annular combustible gas chamber 41 in the mixer 31.

The heating oxygen is discharged from the forward end 32 of the mixer nozzle 33 through a central passage 42 therein. The oxygen discharge from the end of the nozzle 33 mingles with the combustible gas which flows from chamber 41 around the end of the mixer nozzle 33 and the two gases flow from the mixer outlet or throat 43 to a mixing tube 44 connected at one end to the forward valve body 3. I prefer to make the central passage 42 in the mixer nozzle as large as the mixer throat 43 so that in the event of a backfire the gases in the throat can pass backward into the central mixer passage 42 without being retarded due to a reduction in area of said passage as compared to the area of said throat 43. The other end of the mixing tube 44 is connected to a distributing chamber 45 in the blowpipe head 4. The combustible gas mixture flows from the distributing chamber 45 through a plurality of combustible gas mixture passages 46 in the blowpipe nozzle 21 at the end of which the mixture may be ignited in the usual manner to produce a heating flame.

A similar type of blowpipe is shown in Figures VIII to XV but the tubes are arranged in a different manner. For the purpose of rendering the blowpipe flashback resistant, the required length of and volume in the heating oxygen conduit between the heating oxygen control valve and the end of the mixer nozzle is obtained by extending the preheating oxygen conduit from the control valve to the blowpipe head and returning the conduit to a mixer located a determined distance from the blowpipe head.

In the blowpipe shown in Figs. VIII to XV the oxygen is supplied thereto through a nipple 50 and a connecting nut 51 connected in series to a valve body 52 at the rear end of the blowpipe handle 53. A cutting oxygen valve 54 is retained in a valve chamber 55 in the valve body 52 by means of the connecting nut 51 screwed into a counterbore at the outer end of the valve chamber 55. A spring 56 is compressed between the inner end of the connecting nut 51 and the outer end of the valve 54 and normally retains the valve on its seat 57. A central bore 58 through the connecting nut 51 conducts oxygen from the nipple 50 to the valve chamber 55.

Oxygen for cutting purposes may be released from the valve chamber 55 by depressing a cutting oxygen valve lever 59 pivoted on a pin 60 in a block 61 at the forward end of the handle 53. Movement of the lever 59 is transmitted to the cutting oxygen valve 54 through a motion transmitting mechanism comprising a link 62 pivoted at one end to the lever 59 and at the other end to one arm of a bell-crank lever 63 which is pivoted on a pin 64 in a block 64 in the blowpipe handle 53. Motion is transmitted from the other arm of the bell-crank lever 63 to a rod 65 which extends from the arm of the bell-crank lever to the cutting oxygen valve 54. The rod 65 is slidably supported in a plug 66 which closes an opening in the wall of the outlet passage 67 of the valve seat 57.

Upon depressing the cutting oxygen valve lever 59 the cutting oxygen valve 54 is pushed away

from its seat 57 and oxygen flows from the valve chamber 55 and the outlet passage 67 to a transverse passage 68 in the valve body 52. A tube 69, connected to the transverse passage 68, conducts the oxygen therefrom to the blow pipe head 70 and delivers the oxygen to a cavity 71 in the blow head. A cutting nozzle 72 is secured to the blow pipe head by a clamping nut 73. A central oxygen passage 74 is formed in the nozzle which receives oxygen from the cavity 71 and delivers it to the metal to be cut.

The heating oxygen is conducted through a heating oxygen passage 15 which branches off from the main oxygen passage 58 in the cutting valve chamber 55 as shown in Fig. XI. A valve 16 is located in the heating oxygen passage 15 in the valve body 52 to control the supply of heating oxygen delivered to the gas mixer 77.

In order to obtain the desired length and volume in the passage between the heating oxygen control valve 16 and the discharge end 78 of the mixer nozzle 79 to prevent flashbacks, the oxygen is conducted from the outlet passage 80 of the control valve 16 to the blowpipe head 70 through a tube 81 which extends between the outlet passage 80 in the valve body 52 to a transverse bore 82 in the blowpipe head. The heating oxygen is then returned from the transverse bore 82 to a chamber 83 in the rear end of the mixer bore 84. The oxygen is conducted between the two points through a tube 85 which extends between the transverse bore 82 in the blowpipe head 70 and the valve body 52 which is provided with a passage 86 which conducts the oxygen from the tube 85 to the chamber 83 in the rear end of the mixer bore 84 closed by a plug 87 screw threaded therein.

A combustible gas such as acetylene is supplied to the gas mixer 77 through a nipple 88 which is connected to a combustible gas valve casing 89 having a valve 90 therein for controlling the flow of gas therethrough. The outlet of the valve casing 89 is connected to a passage 91 in the valve body 52 which leads to the annular chamber 92 in the gas mixer 77.

The heating oxygen discharged from the chamber 83 in the rear end of the mixer bore 84 passes through a central bore 93 in the mixer nozzle 79 and mixes with the combustible gas 50 which flows from the annular combustible gas chamber 92 in the mixer 77. The oxygen mixes with the combustible gas and forms a gas mixture which is conducted from the mixer 77 through a tube 94 which is connected to a distributing chamber 95 in the blowpipe head 70. The combustible gas mixture flows from the distributing chamber 95 through the combustible gas mixture passage 96 in the blowpipe nozzle 72. The mixture may be ignited for heating purposes in the usual manner upon being discharged from the blowpipe.

The foregoing illustrates two examples of the application of my invention to a blowpipe adapted to utilize medium pressure acetylene with a mixer nozzle having little or no injector action or in a case where the backfiring gases are forced backward into the heating oxygen passage for the purpose of preventing flashbacks. The more general application of my invention is diagrammatically illustrated in Fig. XVI. It is here shown that my invention is also applicable to a blowpipe utilizing low pressure acetylene or other combustible gas with an injector mixer nozzle in which case the backfiring gases are forced up the

combustible gas passage for the purpose of preventing flashbacks.

As illustrated in Fig. XVI the blowpipe is adapted for use with both systems and for convenience only the heating gas passages are shown. The oxygen is supplied to the blowpipe through the hose O. The oxygen is controlled by the valve V. The valve V may form the nearest constriction in this passage to the mixing point M in the mixer. As shown, however, the valve V is placed in rear of such a constriction C_o, the inlet to a reservoir R_o. The reservoir R_o is inserted in the passage D_o between the constriction C_o and the mixing point M as a substitute for the coiled tube 28 in Figs. I to VII and as a means of reducing the length of the corresponding tube in Figs. VIII to XV. The reservoir R_o is a convenient means of providing the necessary volume in the passage D_o, including the length of the reservoir R_o, for a given minimum length of D_o to allow the recession of backfiring gases thereinto and thereby prevent flashbacks as will be hereinafter explained.

The combustible gas is supplied to the blowpipe from a hose A through a valve V, a constriction C_a at the inlet of a reservoir R_a in a passage D_a leading to the mixing point M at the end of the mixer nozzle. The location of the elements in the combustible gas passage D_a corresponds to and may perform the same function as the corresponding elements in the heating oxygen passage D_o in the event the backfiring gases travel backward into the passage D_a, but the length and/or volume of the passage D_a should be made greater under like conditions. Upon mixing at the mixing point M the combustible mixture of oxygen and a combustible gas flows through the combustible mixture passage D_m to the discharge end of the burner nozzle N.

As herein used the word constriction indicates a point such as C_o or C_a nearest to the mixing point which offers a material resistance to the backward flow of gases and other than the resistance due to normal tube wall friction. The passage D_o is the heating oxygen passage extending rearwardly from the discharge end of the mixer nozzle, that is, from the mixing point to the nearest constriction which in the usual case is the heating oxygen valve. D_a indicates a portion of the combustible gas passage situated in a manner corresponding to D_o. D_m is the combustible mixture passage extending from the mixing point to the end of the burner nozzle N.

By properly proportioning the length and volume of the passages D_m, D_o and D_a in respect to each other for a given combustible gas consumption, a blowpipe having good flashback resistance can be obtained. These proportions may be determined upon the following principles. A backfire produces pressure in D_m and will force the burning, burned and unburned mixture up either the oxygen passage D_o or the combustible gas passage D_a or both of said passages depending upon the pressure created thereby in the mixing tube throat, and the resistance offered to the backward flow of the gases in the passages D_o and D_a. When the backfiring gases are forced backward into either the oxygen passage D_o or the combustible mixture passage D_a the further formation of a combustible mixture is prevented until the backfire gases are forced forwardly out of each of the passages D_o and D_a. If a sufficient time elapses between the recession of the backfiring gases into the passages D_o and D_a and the return of these gases to the mixing point

- to permit them to be burned out or extinguished before the last of the backfiring gases return to the mixing point, then there will be no flashback unless the mixing tube or particles of carbon 5 remaining therein are heated up to the ignition point of the gases. The elapsed time is increased as the pressure in the mixer throat is increased and as the resistance beyond the throat is decreased.
- 10 The pressure created in the mixing tube throat may be controlled by the length and volume of the combustible mixture passage D_m . I have found by increasing the length of this passage and by increasing its volume as by inserting a 15 chamber in this passage the pressure of the backfire in the mixing tube throat has been increased and good flashback resistance has been obtained with reduced lengths and volumes in the gas passages D_o or D_a .
- 20 The resistance offered to the backward flow of the backfiring gases in the oxygen passage and combustible gas passage is increased by constrictions in these passages within a minimum distance back from the mixing point or the discharge 25 end of the mixer nozzle. The resistance to the backward flow of the backfiring gases in the passages D_o and D_a is also increased by an increase in the normal pressure of the gases in those passages and by a decrease in the volume in the passages D_o and/or D_a below a certain minimum for a given length and pressure therein. When a 30 backfire occurs the backfiring gas will travel most readily into the passage offering the least resistance.
- 35 From the standpoint of preventing flashbacks it is desirable that the backfiring gases travel backwards into the oxygen passage D_o in preference to the combustible gas passage D_a and that the unburned mixture be retained in the oxygen 40 passage D_o until it has been completely burned and until after the combustible gas has resumed its forward flow and returned to the mixing point. However, blowpipes can be made flashback resistant by causing the backfiring gases to travel 45 backward into the combustible gas passage until the mixture is completely burned out before returning to the mixing point and after the return of the oxygen to said point. As the combustible mixture burns more slowly in the combustible 50 gas passage than it does in the oxygen passage, it is necessary to retain the combustible mixture in the combustible gas passage D_a a greater period of time to allow it to completely burn before returning to the mixing point than it is necessary 55 to retain the combustible mixture in the oxygen passage D_o under like conditions. Furthermore when the oxygen returns to the point of mixing before the combustible gas arrives, it may sustain the combustion of any burning portions of 60 carbon in that region and it may sustain the combustion until the acetylene returns to that region and be ignited in the presence of the oxygen and thereby cause a flashback. In view of the sustained combustion of the carbon particles in the 65 region of the mixing point it may also be necessary to cause a further delay of the return of the combustible gas to the mixing point. In view of the foregoing explanation it is necessary to delay the return to the mixing point of only the last 70 component of the combustible mixture which reaches the mixing point after a backfire until after the flame in that component has been extinguished and until after any matter contained in the mixing tube and in the vicinity of the mixing 75 point has been cooled below the temperature

of ignition of the combustible mixture, although if desired the return of both components of the combustible mixture to the mixing point may be delayed as shown in Fig. XVI to obtain good flashback resistance.

Referring to Fig. XVI in connection with the examples A, B, and C shown in the table below, in the case of a blowpipe utilizing medium pressure acetylene with a consumption up to 50 cu. ft. of acetylene per hour excellent flashback resistance was obtained. In these examples no provision was made for the backfiring gases to recede into the acetylene passage. Therefore this passage was constructed as usual. In each example the length of D_m was 7" and its volume 15 was .16 cu. in.

Example	A	B	C
D_o Length in inches.....	13.8	17.6	19.6
D_o Volume in cu. inches.....	33.70	9.00	3.47
d_o Length in inches.....	3.8	7.6	9.6
d_o Volume in cu. inches.....	.16	.35	.45

In each of the above examples when d_o was 25 reduced in length by more than one inch, thereby reducing D_o by the same amount, the flashback resistance was lowered. I have found that the length and volume of the passage D_o and also D_a 30 may be increased without reducing the flashback resistance of the blowpipe.

I have also found that when the cu. ft. of consumption of acetylene is increased in a blowpipe 35 designed to give good flashback resistance for a certain maximum consumption and a minimum length and volume in the passages D_o or D_a for a given D_m that the length and/or volume in the passages D_a , D_o or D_m must be increased to obtain the same degree of flashback resistance.

While I have illustrated my invention in connection with a cutting blowpipe, my invention is 40 equally applicable to welding blowpipes and the invention may be applied to either the oxygen or the combustible gas passage for preventing flashbacks. Also a wide departure may be made 45 from the examples as given herein. I therefore wish to limit my invention only by the scope of the claims appended hereto.

I claim:

1. A flashback resistant blowpipe adapted to 50 utilize a combustion supporting gas and a combustible gas for producing a heating flame, said blowpipe comprising a mixer having a nozzle and an outlet throat therein; a burner nozzle; a conduit including said mixer throat for conducting the combustible gas mixture to said burner nozzle; a supply conduit for conducting a combustion supporting gas to said mixer nozzle; a supply conduit for conducting a combustible gas to said mixer; a portion of said supply 55 conduit for combustion supporting gas connecting directly with said mixer nozzle and being elongated and having a minimum internal cross-sectional area substantially as large as the internal area of said mixer throat; said elongated portion being free from constrictions therein and having sufficient length and volume therein to receive the unburned backfiring combustible mixture and to retain said backfiring combustible mixture therein until said mixture has been completely burned and until said combustible mixture conduit and any particles remaining therein have been cooled below the ignition temperature 60 of said combustible mixture.

2. A flashback-resistant blowpipe adapted to 65

utilize a combustion supporting gas and a combustible gas for producing a heating flame, said blowpipe comprising a burner nozzle; a mixer; a conduit for conducting the combustible gas mixture to said burner nozzle; a supply conduit for conducting a combustion supporting gas to said mixer; a supply conduit for conducting a combustible gas to said mixer; a portion of one of said supply conduits connecting directly with 10 said mixer and being elongated; said elongated portion being free from constrictions and having sufficient length and internal capacity to freely receive an unburned backfiring combustible mixture and retain the same therein until completely burned, and until said combustible mixture conduit and any particles of carbon therein have cooled below the ignition temperature of the combustible mixture.

3. A flashback-resistant blowpipe comprising a 20 burner nozzle; a gas mixer; a conduit for conducting a combustion-supporting gas to said mixer; a conduit for conducting a combustible gas to said mixer; a conduit for conducting a combustible gas mixture from said mixer to said burner nozzle; a portion of one of said first two conduits immediately in the rear of said mixer being elongated and free from constrictions adapted to substantially retard the backward flow of gas therein and having sufficient length and 25 internal capacity to freely receive an unburned backfiring combustible mixture and retain the same therein until completely burned, such elongated portion including a coil, and the other of said two conduits having a part thereof 30 rounded by said coil.

4. In a flashback-resistant blowpipe, the combination of a blowpipe head; a burner nozzle secured to said head; a valve body; a gas mixer within said valve body; a handle secured to said 40 valve body; means for conducting a combustible mixture from the outlet of said mixer to said burner nozzle, such conducting means including a tube secured to said head and to said valve body; a conduit for supplying a combustible gas to said mixer; a conduit for supplying a combustible gas to said mixer; and valves mounted on said valve body and severally controlling the flow of gas through said conduits, one of said conduits being elongated between its 45 control valve and said mixer and including a coil within said handle, such elongated conduit being free from constrictions adapted substantially to retard the backward flow of gas therein and

having sufficient length and internal capacity to receive an unburned backfiring combustible mixture and retain said backfiring combustible mixture therein until completely burned, and until such combustible mixture conducting means and any particles of carbon therein have cooled below the ignition temperature of the combustible mixture.

5. A flashback-resistant blowpipe comprising a handle; a gas mixer carried by said handle and including a mixer nozzle; a blowpipe head secured to but spaced from said handle; a burner nozzle connected to said head; a conduit for conducting a combustible gas mixture from the outlet of said mixer to said burner nozzle; a valve 15 carried by said handle and controlling the supply of heating oxygen to said mixer; and a conduit for such heating oxygen extending from said valve to said head and returning to the inlet of said mixer nozzle, such heating oxygen conduit being free from constrictions and having sufficient length and internal capacity to receive an unburned backfiring combustible mixture and retain the same therein until completely burned.

6. In a flashback-resistant blowpipe, the combination of a blowpipe head having a bore; a burner nozzle secured to said head; a valve body; a gas mixer carried by said valve body; means for conducting a combustible mixture from said mixer to said burner nozzle, such conducting 25 means including a tube secured to said head and to said valve body; a conduit for supplying a combustible gas to said mixer; a conduit for supplying a combustion-supporting gas to said mixer; and valves mounted on said valve body 30 and severally controlling the gas flow through said conduits; one of said conduits being elongated between its control valve and said mixer and including two sections of tubing extending longitudinally of the combustible mixture 35 conducting tube and secured to said valve body and to said head in communication with said bore in said head, such elongated conduit being free from constrictions and having sufficient length and internal capacity to receive an unburned 40 backfiring combustible mixture and to retain said backfiring combustible mixture therein until completely burned and until such combustible mixture conducting means and any particles of carbon therein have cooled below the ignition 45 temperature of the combustible mixture.

WILGOT J. JACOBSSON.
